237,022

BARBER'S APRON

Nathaniel Mathis, 4014 Vine St.,
Bradbury Heights, Md. 20027

Filed Mar. 8, 1973, Ser. No. 337,861

Term of patent 14 years

Int. Cl. D2—02

U.S. Cl. D2—229

FIG. 1

FIG. 2

FIG. 3

FIG. 1 is a front elevational view of a barber's apron showing my new design;

FIG. 2 is a rear elevational view thereof; and
FIG. 3 is a side elevational view.

I claim:

The ornamental design for a barber's apron, as shown.
